Albert W. Hull,
by *Albert C. Davis*
His Attorney

UNITED STATES PATENT OFFICE.

ALBERT W. HULL, OF SCHENECTADY, NEW YORK, ASSIGNOR TO GENERAL ELECTRIC COMPANY, A CORPORATION OF NEW YORK.

DYNATRON SYNCHRONOUS DETECTOR.

Application filed November 13, 1920, Serial No. 423,952. Renewed February 3, 1925.

To all whom it may concern:

Be it known that I, ALBERT W. HULL, a citizen of the United States, residing at Schenectady, in the county of Schenectady, 5 State of New York, have invented certain new and useful Improvements in Dynatron Synchronous Detectors, of which the following is a specification.

My present invention relates to detectors 10 for producing a desired indication of signaling currents and more particularly to detectors which are adapted to produce an audible indication of signaling currents of inaudible frequency such for example, as 15 high frequency continuous waves commonly employed for radio signaling purposes.

The novel features which I believe to be characteristic of my invention are set forth with particularity in the appended claims, 20 the invention itself, however, both as to its construction and mode of operation, together with the objects and advantages thereof will best be understood by reference to the following description taken in connection with 25 the accompanying drawing in which Figs. 1 and 2 are diagrammatic representations of two different circuit arrangements which may be employed in carrying my invention into effect.

30 In Fig. 1, I have represented a system for receiving and detecting radio signals of the continuous wave type. As shown in the drawing this system comprises an electron discharge device 1, which is preferably of the negative resistance type described and claimed in my United States Patent 1,387,985, August 16, 1921. This device comprises an evacuated envelope 1 containing a filamentary cathode 2, an electrode 3, which for convenience of description I call the anode, and a third electrode 4, which surrounds the cathode and anode. A source of potential 5 supplies current to the anode 2 for heating it to such a temperature that it will emit the desired quantity of electrons. The source of potential 6 maintains the anode 3 at a constant positive potential with respect to the cathode 2. A third source of potential 7 is impressed between 45 cathode 2 and third electrode 4 for adjusting the potential of the third electrode 4 to such a value that the current flowing between the cathode and third electrode will vary inversely as the potential which is applied to the circuit between cathode and 55 third electrode. A magnetizing coil 8, which is indicated at the right of the device, but which in practice surrounds the receptacle in which the electrodes 2, 3 and 4 are located, is provided for the purpose 60 of furnishing a magnetic field for controlling the flow of electrons between the cathode 2 and third electrode 4.

In the operation of the system signaling currents received upon the antenna 9 are 65 impressed from the primary 10 of a transformer upon a resonant receiving circuit, which includes the inductance 11 and condenser 12. This resonant circuit being included in the external circuit between cathode 2 and third electrode 4, the potentials impressed thereon from the antenna tend to produce variations in the current between cathode 2 and third electrode 4. In the absence of any controlling means, however, 70 these current variations will be high frequency variations corresponding to the high frequency variations set up in the antenna by the signaling currents, and will produce no audible indication in the telephone receiver 13 which is included in the circuit between cathode and third electrode. 75

When, however, a magnetizing field is produced by means of the coil 8, the current between cathode and third electrode will be caused to vary in accordance with variations 80 in the magnetic field. If current is supplied to the magnetizing coil 8 by means of an alternating source 14 having a frequency equal to one-half that of the frequency of the signals which are received the current between cathode and third electrode will be caused to vary in accordance with the variations supplied by the source 14. The current flowing in the circuit between 85 cathode and third electrode then instead of being a pure alternating current of the signaling frequency will have a direct current component introduced therein, that is, impulses of one polarity will be suppressed or greatly diminished while impulses of the opposite polarity will flow between the electrodes with undiminished or slightly diminished amplitude. This direct current will continue as long as a signal is being 90 received and will not produce any effect 95

100

105

upon the telephone receiver 13. It would, however, be capable of controlling the operation of any indicating device which may be operated by a steady direct current.

If, on the other hand, the frequency of the source 14 differs from one-half that of the signals to be received by an amount within the audible range, the current in the circuit between the cathode and third electrode will have introduced therein in addition to the high frequency component an alternating current component whose frequency is determined by the difference in frequency between that of the source 14 and half the frequency of the signaling current. This low frequency current component will give the desired audible indication in the telephone receiver 13.

In some cases it may be desirable to employ in addition to the alternating magnetic field furnished by the coil 8 a constant magnetic field which may be applied by means of the coil 15, which is supplied by current from a direct current source 16, adjustable resistance 17 being included in this circuit for adjusting the strength of the magnetic field to a desired value. In this case the source 14 may be of a frequency differing from the frequency of the signaling current by an amount within the audible range. The device 1 will preferably be so adjusted that it will have a sufficient value of negative resistance to compensate for the resistance losses in the antenna and in the receiving circuit so that the device will act not only as a detector but also as an amplifier.

In Fig. 2 I have shown an arrangement which differs from that of Fig. 1 in that the local high frequency oscillations are produced in the circuit between cathode and third electrode, and the signaling current is utilized to produce a magnetic field in the device. In this case the circuit between cathode and third electrode includes inductance 18 in parallel with the capacity 19, this inductance and capacity forming an oscillatory circuit which may be tuned to the desired frequency. When the device 1 is adjusted to operate as a negative resistance oscillations will normally be produced in this oscillatory circuit. When the signaling currents to be detected are impressed upon the coil 20, thereby producing a magnetic field in the device, the amplitude of the high frequency oscillations which are produced will be varied in accordance with the variations in this magnetic field.

The operation of the device in so far as the effect upon the current between cathode and third electrode is concerned will be the same as in the case of Fig. 1. If it is desired to employ a constant magnetic field in addition to the variable field produced by the signaling currents a source of direct current 21

may be supplied to the magnetizing coil 20, as indicated. In this case a condenser 22 may be inserted in the circuit to prevent the source 21 from being short circuited by the coil 11 and a choke coil 23 inserted in series with the battery to prevent the high frequency current from being short circuited through the battery. The telephones 13 are preferably shunted by means of condenser 24 for the purpose of bypassing the high frequency component of the current flowing in the circuit therein between the cathode and third electrode.

While I have described my invention with particular reference to a system for receiving and detecting continuous wave radio signals it is apparent that it is not limited in its utility to this particular use, but that it may be employed for detection of signaling currents of inaudible frequency transmitted over wire lines or for the detection of signaling currents of a frequency below audibility. While I have indicated only two circuit arrangements whereby my invention may be carried into effect it will be obvious to those skilled in the art that many modifications in the circuit arrangements employed as well as in the particular form of apparatus used may be made without departing from the scope of my invention as set forth in the appended claims.

What I claim as new and desire to secure by Letters Patent of the United States, is:

1. The combination in a system for detecting high frequency signaling currents of an electron discharge device having an electron emitting cathode, an anode, and a third electrode enclosed in an evacuated envelope, an electric circuit between cathode and third electrode, sources of potential applied to the electrodes of said device in such a way that the current in said circuit will increase and decrease inversely as the potential between cathode and third electrode, a magnetizing coil associated with said device for producing a magnetic field in the space between cathode and third electrode, a second circuit associated with said magnetizing coil, means for producing locally high frequency oscillations of a frequency different from that of the signaling currents to be detected, means for supplying the locally produced high frequency oscillations to one of said circuits, and means for supplying signaling currents to the other circuit.

2. The method of operating an electron discharge device, having an electron emitting cathode and a cooperating electrode enclosed in an evacuated receptacle and having an oscillatory circuit associated with said electrodes, which consists in producing a flow of electrons between said electrodes producing by means of a high frequency signaling current to be detected a magnetic field in a direction substantially at a right

angle to the paths of said electrons, producing high frequency oscillations in said oscillatory circuit of a frequency different from that of the signaling currents to be detected, 5 and producing an indication of the resulting current flowing between said electrodes.

3. The method of operating an electron discharge device, having an electron emitting cathode and a cooperating electrode enclosed in an evacuated receptacle and having an oscillatory circuit associated with said electrodes, which consists in producing a flow of electrons between said electrodes, producing by means of a high frequency signaling current to be detected a magnetic field in a direction substantially at a right angle to the paths of said electrons, producing high frequency oscillations in said oscillatory circuit and producing an indication 10 of the resulting current flowing between said electrodes.

4. The method of operating an electron discharge device, having an electron emitting cathode and a cooperating electrode enclosed in an evacuated receptacle and having an oscillatory circuit associated with said electrodes, which consists in producing a flow of electrons between said electrodes, producing by means of a signaling current 15 to be detected a magnetic field in a direction substantially at a right angle to the paths of said electrons, producing oscillations in said oscillatory circuit of a frequency different from that of the signaling currents to be detected, and producing an indication of the resulting current flowing 20 between said electrodes.

5. The method of operating an electron discharge device, having an electron emitting cathode and a cooperating electrode enclosed in an evacuated receptacle and having an oscillatory circuit associated with said electrodes, which consists in producing a flow of electrons between said electrodes, producing by means of a signaling current 25 to be detected a magnetic field in a direction substantially at a right angle to the paths of said electrons, producing oscillations in said oscillatory circuit and producing an indication of the resulting current flowing 30 between said electrodes.

6. The combination in a system for detecting high frequency signaling currents of an electron discharge device having an electron emitting cathode, an anode and a third electrode enclosed in an evacuated receptacle, an oscillatory circuit connected between cathode and third electrode, sources of potential applied to the electrodes of said device in such 55 a way that the current between cathode and third electrode will increase and decrease inversely as the potential between cathode and third electrode, said oscillatory circuit being so proportioned that high frequency 60 oscillations will be produced therein, a mag-

netizing coil associated with said device and adapted to produce a magnetic field in the space between cathode and third electrode, means for supplying to said magnetizing coil the high frequency signaling currents 70 to be detected, and means for producing an indication of the resultant current in the circuit between cathode and third electrode when the signaling currents are supplied to the magnetizing coil. 75

7. The combination in a system for detecting high frequency signaling currents of an electron discharge device having an electron emitting cathode, an anode, and a third electrode enclosed in an evacuated receptacle, 80 an oscillatory circuit connected between cathode and third electrode, sources of potential applied to the electrodes of said device in such a way that the current between cathode and third electrode will increase and decrease inversely as the potential between cathode and third electrode, said oscillatory circuit being so proportioned that high frequency oscillations will be produced therein of a frequency different from that of the signaling currents to be detected, a magnetizing coil associated with said device and adapted to produce a magnetic field in the space between cathode and third electrode, means for supplying to said magnetizing coil the high frequency signaling currents to be detected, and means for producing an indication of the resultant current in the circuit between cathode and third electrode when the signaling currents are supplied to the magnetizing coil. 95

8. The combination in a system for detecting high frequency signaling currents of an electron discharge device having an electron emitting cathode, an anode, and a third electrode enclosed in an evacuated receptacle, an oscillatory circuit connected between cathode and third electrode, sources of potential applied to the electrodes of said device in such a way that the current between cathode and third electrode will increase and decrease inversely as the potential between cathode and third electrode, said oscillatory circuit being so proportioned that oscillations will be produced therein, a magnetizing coil associated with said device and adapted to produce a magnetic field in the space between cathode and third electrode, means for supplying to said magnetizing coil the signaling currents to be detected, and means for producing an indication of the resultant current in the circuit between cathode and third electrode when the signaling currents are supplied to the magnetizing coil. 105

9. The combination in a system for detecting high frequency signaling currents of an electron discharge device having an electron emitting cathode, an anode, and a third electrode enclosed in an evacuated receptacle, an 110

oscillatory circuit connected between cathode and third electrode, sources of potential applied to the electrodes of said device in such a way that the current between cathode and third electrode will increase and decrease inversely as the potential between cathode and third electrode, said oscillatory circuit being so proportioned that oscillations will be produced therein of a frequency different from that of the signaling currents to be detected, a magnetizing coil associated with said device and adapted to produce a magnetic field in the space between cathode and third electrode, means for supplying to said magnetizing coil the signaling currents to be detected, and means for producing an indication of the resultant current in the circuit between cathode and third electrode when signaling currents are supplied to the magnetizing coil.

10. The combination in a system for detecting high frequency signaling currents of an electron discharge device having a plurality of electrodes and a plurality of circuits associated with said device, one of said circuits having a negative resistance included therein, a second of said circuits including means for varying the value of the negative resistance of the first, means for impressing signaling currents upon one of the circuits associated with said device, and means for producing local oscillations in another of said circuits of a frequency differing from that of the signaling currents.

11. The combination in a system for detecting high frequency signaling currents of an electron discharge device having a plurality of electrodes and a plurality of circuits associated with said device, one of said circuits having a negative resistance included therein, a second of said circuits including magnetic means for varying the value of the negative resistance of the first, means for impressing signaling currents upon one of the circuits associated with said device, and means for producing local oscillations in another of said circuits of a frequency differing from that of the signaling currents.

12. The combination in a system for detecting high frequency signaling currents of an electron discharge device having a

plurality of electrodes and a plurality of circuits associated with said device, one of said circuits which is connected between two of the electrodes of said device having a negative resistance included therein, a second of said circuits including means for varying the value of the negative resistance of the first, means for impressing signaling currents upon one of the circuits associated with said device, and means for producing local oscillations in another of said circuits of a frequency differing from that of the signaling currents.

13. The combination in a system for detecting high frequency signaling currents of an electron discharge device having a plurality of electrodes enclosed in an evacuated receptacle and a plurality of circuits associated with said device, one of said circuits which is connected between two of the electrodes of said device having a negative resistance included therein, a second of said circuits including a magnetizing coil surrounding said receptacle for varying the value of the negative resistance of the first, means for impressing signaling currents upon one of the circuits associated with said device, and means for producing local oscillations in another of said circuits of a frequency differing from that of the signaling currents.

14. The combination in a system for detecting high frequency signaling currents of an electron discharge device having a plurality of electrodes enclosed in an evacuated receptacle and a plurality of circuits associated with said device, one of said circuits which is connected between two of the electrodes of said device having a negative resistance included therein, a second of said circuits including a magnetizing coil surrounding said receptacle for varying the value of the negative resistance of the first, means for impressing signaling currents upon the second of the circuits associated with said device and means for producing local oscillations in the first of said circuits of a frequency differing from that of the signaling currents.

In witness whereof, I have hereunto set my hand this 12th day of November 1920.

ALBERT W. HULL.
